UNITED STATES PATENT OFFICE.

EDWARD E. HINRICHSEN, OF EAST ORANGE, NEW JERSEY, ASSIGNOR, BY MESNE ASSIGNMENTS, TO WESTERN ELECTRIC COMPANY, INCORPORATED, A CORPORATION OF NEW YORK.

TELEPHONE SYSTEM.

1,205,538.

Specification of Letters Patent. Patented Nov. 21, 1916.

Application filed October 8, 1915. Serial No. 54,725.

To all whom it may concern:

Be it known that I, EDWARD E. HINRICHSEN, a citizen of the United States, residing at East Orange, in the county of Essex and State of New Jersey, have invented new and useful Improvements in Telephone Systems, of which the following is a full, clear, concise, and exact description.

This invention relates to telephone systems, and more particularly to such systems of the type wherein, in establishing connections between subscribers, three or more central and local offices are involved.

The object of this invention is to provide a telephone system in which connections may be established from one subscriber's line through two central offices and one of a plurality of local offices to another subscriber's line without the intervention of an operator at one of the central offices and with the use of a minimum amount of apparatus.

In accordance with this invention, there is provided a main trunk circuit extending from a first to a second central office, and local trunk circuits and associated call wire circuits, one of each extending from the second central office to each of a plurality of local offices. At the second central office there is a step-by-step selecting device associated with the main trunk circuit and controlled thereover from an impulse transmitter associated with a link circuit connected with the main trunk circuit at the first central office, to select a local trunk circuit extending to one of the local offices and thereafter to control the connection of the main trunk circuit with an associated call wire circuit of the selected local trunk circuit.

This invention is an improvement over that disclosed and claimed in an application Serial No. 54,336, filed October 6, 1915, by me. The present invention is a decided improvement over that disclosed and claimed in application Serial No. 54,336, in that the present invention provides for a greatly increased number of offices local to the second central offices, any one of which may be selected from the first central office. The present invention also accomplishes this re-

sult by the use of a much smaller amount of apparatus.

This invention will be more fully understood by reference to the accompanying drawings illustrating one embodiment thereof. To obtain a clear idea of the entire system, the figures should be placed side by side in the following order from left to right,—1, 2, 3, 4.

As shown in the drawings, this invention comprises a main trunk circuit B, the outgoing end of which is located at a first or originating central office X, and the incoming end of which terminates in a second central office Y. Located at central office X is a cord circuit A used to complete connections from an originating subscriber (not shown), to the incoming end of the main trunk circuit B. Extending from the second central office Y to local offices E, F, G and H are local trunk circuits C and associated call wire circuits D, there being one local trunk circuit C and an associated call wire circuit D for each local office. The cord circuit A, shown in Figure 1, and the outgoing end of the main trunk circuit B, shown in Fig. 2, are located at the first central office X, while the incoming end of the main trunk circuit B, shown in Fig. 3 and 86 to the left of the dotted line in Fig. 4, is located at the second central office Y. The incoming end of the local trunk circuit C, shown between the dotted lines in Fig. 4, is located at the local office F. Only one 85 complete local trunk circuit C and its associated call wire circuit D are shown in the drawing. This local trunk circuit and associated call wire circuit are those extending to the local office F. The equipment for the local trunk circuits C and associated call wire circuits D extending to the local offices E, G and H is exactly the same as that shown for the same circuits extending to local office F.

At the central office X, there is located an impulse transmitter 36 (shown within the dotted lines). This transmitter 36 is common to an operator's position and comprises a starting relay 44, an interrupter, a selecting key for each local office, and a pair of relays for each local office. The inter-

rupter comprises two relays 45 and 46. When starting relay 44 is operated, relay 45 operates, which in turn causes the operation of relay 46. Relay 46, in operating, releases relay 45, which in turn releases relay 46. Relay 45 thereupon again operates. This cycle of operations for relays 45 and 46 continues in this manner as long as starting relay 44 remains operated. Relays 45 and 46 are slightly sluggish in operation so that these relays will control the short current impulses, the duration of which must be such as to permit of the proper operation of selecting apparatus in the main trunk circuit B. Selecting keys 40, 41, 42 and 43 correspond respectively to the local offices E, F, G and H. Key 40 controls relays 47 and 48; key 41 controls these two relays and relays 49 and 50; key 42 controls these four relays and relays 51 and 52; and key 43 controls these six relays and relays 53 and 54. One short and one long impulse is sent out by the transmitter 36 when key 40 is actuated; two short and one long impulse when key 41 is actuated, three short and one long impulse by the actuation of key 42, and four short and one long impulse by the actuation of key 43. Should it be desired to equip the impulse transmitter 36 for selecting more than four local offices, there should be added to the equipment shown, one key and two relays (similar to any pair 47 and 48 or 49 and 50, etc.) for each additional local office.

At the second central office Y there is located a step-by-step selector (shown within the dotted line), controlled from the impulse transmitter 36. This selector 60 comprises an operating or stepping magnet 28 having an armature 61 operating a stepping pawl 62. Each time that stepping magnet 28 is energized, stepping pawl 62 engages a ratchet wheel 63 to advance one step a contact arm or wiper 64 rotatable with the ratchet wheel 63. A holding pawl 65 normally engages the ratchet wheel 63 to hold wiper 64 in advanced position. The holding pawl 65 is controlled by a release magnet 30 which, upon being energized, causes the disengagement of the holding pawl and the ratchet wheel, whereupon the ratchet wheel, due to the action of a spiral spring 68, returns the wiper 64 to normal position, as shown in the drawing. The selector has two off-normal contacts 67 and 67^a and four contacts to which are connected conductors extending to the windings of relays 55 and 56, which control the connection of the main trunk circuit B to the local trunk and associated call wire circuits extending respectively to the local offices E, F, G and H. The selector, obviously, may be equipped with additional contacts to care for as many local offices as particular conditions may warrant.

Assuming that the operator at the first central office has received a call for a subscriber whose line terminates in local office F, the operator will insert calling plug 6 into jack 7 of the main trunk circuit B, 70 thereby energizing relay 15 over a circuit from battery through the winding of relay 38, sleeve contacts of plug and jack, both windings of relay 15, and the normal contact of relay 16 to ground. Relay 15, in operating, causes the actuation of relay 17, which connects the talking strands of the main trunk circuit B through to the tip and ring contacts of the jack 7 and opens the circuit of relay 16 at the normal contact of relay 15, thereby preventing the connection of a second cord circuit to the main trunk circuit B during the connection therewith of cord circuit A. The operation of relay 15 also causes the operation of relay 18 over a circuit from battery through the contact of relay 27, left-hand winding of relay 18 and alternate contact of relay 15 to ground. The operation of relay 18 causes the operation of relays 22 and 25 over a circuit from negative signaling battery through contact of relay 18, windings of relays 22 and 23, retardation coil 58, ring conductor of main trunk circuit B, retardation coil 59, windings of relays 24 and 25; and resistance 73 90 to ground. Relay 23 is marginal and does not operate when included in circuit with both windings of relay 25 and resistance 73, but does operate when the right-hand winding of relay 25 and resistance 73 is removed 100 from the circuit. Relay 22 in operating removes the short circuit from the left-hand winding of relay 27. This winding is of high resistance, while the right-hand winding is of low resistance. Relay 24 is polarized, so that it does not operate on negative signaling battery; hence it does not operate when the plug 6 is first inserted in the jack 7, thereby preventing the operation of the operating or stepping magnet 28 of the selector 60. The operation of relay 25 causes the operation of relay 26. The operator at central office X may now actuate listening key 39 and selecting key 41. The actuation of these two keys causes the operation of relay 27 over a circuit from battery through the winding of starting relay 44, lower contact of key 41, upper contact of listening key 39, tip conductors of the cord circuit A and main trunk circuit B, and both windings of relay 27 to ground. Starting relay 44 is marginal, so that it does not operate when included in circuit with both windings of relay 27, but does operate when the high resistance winding is short-circuited. 110 The operation of relay 27 causes the release of relay 18, which in turn causes the release of relay 25. The release of relay 25 releases relay 26. Relay 26, however, is slow in releasing, so that upon the release of relay 25, 120 125 130

are in constant mesh with a bevel-gear 45 on a shaft 46 journaled in a bracket 47 of the frame and having at its rearward end a fixed bevel-gear 48 that meshes with bevel-gear 49 fast on the shaft 29. Clutch 42 is provided with a handle H', and may be called the spool drive and shift mechanism.

By the mechanism described, the spool may be carried transversely around the mandrel, laying the tape or strip spirally or otherwise while the mandrel is rotated. Preferably, for the purpose now particularly intended, the spool is canted, as shown, so that the tape or strip is led to the mandrel 15 at an angle, as shown in Fig. 3, whereby spiral winding is facilitated. When a sufficient number of reverse-spiral windings 50 and 51 have been laid on the mandrel to form a foundation tube for the clencher 20 bead strips 52, straight pieces of vulcanizable rubber of proper cross-sectional contour are put between the rollers 53 and the side of the foundation, and then rolled into place as rings adhérent to the tubular, annular 25 foundation formed by reversely winding the strips or windings 50 and 51, one over the other, spirally and lapping. Each bead-forming strip is simultaneously bent into an annular form and pressed in place by the operation of the rollers 53. When one layer 30 has been spirally wound, a fresh spool or a fresh strip end is pressed on the first-laid strip, and the machine reversed either in respect of the mandrel or spool-carrier, and 35 in any event the tape or strip of frictional material is wound under tension at all stages of building up the carcass.

When the clencher bead-forming strips have been laid or rolled in place, further 40 reverse-spiral windings 54 and 55 (as many alternating, overlapping strips as desired,) are put in place; the rollers 53 being thrown out of use or into idle position, as shown in Fig. 1. In Fig. 5 they are shown in working 45 position. Each is loosely mounted on a journal 56 hinged at 57 to a suitable bracket 58 and held up to their work by a spring 59 that is detachable, so that instead of pulling the journals 56 toward one another and the 50 intermediate portion of the mandrel, the journals may fall away from each other into idle position.

The peripheral work surfaces of the rollers 53 have a shape that corresponds to the 55 exterior wall (of the vulcanizable rubber bead strip) that lies between its upper or grooved edge and its inner edge; and does not engage the outer peripheral wall; that is, the wall of the groove of the bead-forming strip. As these strips are pre-formed with continuous grooves along their outer peripheral edges, it is important not to deform them when they are rolled in place; and it is also desirable that the rollers 53 60 should be held up to their work elastically,

as by spring 59, in order to minimize the deformation due to the pressure of the rollers on the pre-formed bead-strips.

When the carcass has been built up, it is initially in the form of an annular tube with 70 clencher bead rings between the foundation and outer plies. To convert this tube into shoe-form, it is cut around its inner periphery, as by a rotary cutter 59, the mandrel having an inner peripheral slit 60 to permit 75 this operation. The mandrel is preferably of knock-down or collapsible type, comprising segments m , m' and m'' and fasteners m^3 , to permit removal of the shoes at the proper time. After trimming and working 80 the edges of the peripherally slit tube into shape to shape the margins of the outer plies to the foundation and bead rings, or before so doing, the usual rubber, annular tread will be stretched in place around the outer periphery of the carcass; and thereafter the whole may be cured in molds, or be wrapped by the present machine preliminary to vulcanization. It will be observed that the 85 spool is carried positively by its carrier. 90 This is desirable for the best results, because the tapes or strips are thereby pulled tightly in place around the mandrel, tightly upon one another, so as to make the carcass 95 very compact.

If desired, annular bead-supporting rings 100 61 may be used to hold the bead rings in place, these rings to be removed after the initially formed, annular tube is slit around 105 its inner circumference. In practice we find these bead rings important because if they are not used, the bead-forming strips 52 of unvulcanized rubber are apt to be deformed by the compression to which they are, in 110 such case, subjected by the strain of the supplementary or outer windings. The two rings 61 are chamfered and slightly held apart (by the beads 52) at their opposed inner edges, at 62, opposite the inner peripheral cutter-receiving slit 60 of the collapsible mandrel, so that the cutter 59 can pass first through the outer winding or shell, then between the opposed edges of the bead 115 rings 61, and then through the inner winding into the slit 60, which affords a clearance for the cutter. The rings 61 are made of relatively thin stock, and ought to be, as shown, of uniform thickness throughout 120 their annular and cross-sectional extent so as not to involve the use of unnecessary material. Their interior surfaces should be laterally curving, as shown, so as to permit tight winding, over curving surfaces, of the outermost strips. The bead-ring support 125 also functions as a rigid purchase around the inner periphery of the shoe while the exterior strips are being wound in place.

We find, in practice, that in many sizes of shoes made in accordance with the herein-before-described method and by use of the 130

contact and wiper 64 of the selector 60, left-hand winding of relay 57, and contact of relay 29 to ground. Relay 57, in operating, completes a locking circuit for relays 55, 56 5 and 57 through the right-hand winding of relay 57 and contact thereof, and left-hand contact of relay 26 to ground. The operation of relays 55 and 56 extends the main trunk circuit B through to the armatures 10 of relay 70. Relay 56 also closes its contact 74, causing the operation of relays 75 and 76, the operation of the latter causing the lighting of lamp 77 before the operator at the local office F. The operation of relay 15 75 short-circuits the right-hand winding of relay 25 and resistance 73, whereupon marginal relay 23 operates, short-circuiting the right-hand winding of relay 15, causing the operation of relay 38, thereby lighting the 20 supervisory lamp 37.

If the call wire circuit extending to local office F is not busy, the closure of contact 66 of relay 55 causes the operation of relay 70 over a circuit from battery through the 25 contact and left-hand winding of relay 71, contact 66 of relay 55, winding of relay 70, and winding of relay 72 to ground. Relay 70 in operating, completes the connection of the main trunk circuit B to the call wire 30 circuit extending from the second central office to local office F. Relay 70 in operating also closes its contact 69, which short-circuits relay 72, preventing the operation thereof. Relay 71 is marginal and does not 35 operate when included in circuit with the windings of relays 70 and 72, but does operate when included in circuit with the winding of relay 70 only, so that when the winding of relay 72 is short-circuited by the closure of contact 69 of relay 70, relay 40 71 operates. The operator at the central office X may now communicate to the operator at local office F the number of the line to which connection is desired.

The operator at local office F, after being 45 advised of the number of the desired line, inserts the plug of the local trunk circuit C into the jack of the desired subscriber's line, whereupon relay 78 operates, extinguishing the lamp 77. The cutoff relay of the 50 subscriber's line is also operated. The operator at the central office X may now release selecting key 41, thereby releasing relays 44 to 50 inclusive of the impulse transmitter 36 and relays 31 and 32 of the outgoing end of the main trunk circuit B. Relay 18, however, remains operated due to the closure of the contact of relay 27. The release of relay 31 also releases polarized relay 24, which in turn releases relay 55 55 and deenergizes the operating magnet 28 of the selector. The left-hand winding of relay 57 is of low resistance, while the right-hand winding is of high resistance, so that when relay 29 releases relay 55 is

included in circuit with the high resistance winding only of relay 57. Since relay 55 is marginal, it releases when included in circuit with only the high resistance winding of relay 57 and relay 56. Relay 55, in releasing, disconnects the main trunk circuit B from the call wire circuit D and connects it with the local trunk circuit C extending to the local office F. Relay 55 in releasing, also causes the release of relays 70 75 and 71 which restores the call wire circuit D to its normal condition. The operator at the central office X now restores listening key 38 to its original position and actuates ringing key 80 to connect a source 85 of ringing current 81 to the ring side and ground to the tip side of the calling end of the cord circuit A, whereupon relay 82 is actuated, causing the operation of relays 83 and 84. Relay 83, in operating, connects 35 the tip and ring conductors of the main trunk circuit B to the secondary of a transformer 85, the primary of which has been included in closed circuit with a source of alternating current 86 and interrupter 99 90 by the operation of relay 84. High frequency current from the secondary of transformer 85 passes through repeating coil 87 and operates relay 88. Relay 89 is normally energized, so, when relay 88 operates, 95 relay 89 releases, causing the operation of relay 90. Relay 89 is slow in releasing so that it will not release and cause false rings should relay 88 be energized momentarily due to disturbances on the trunk. Relay 90, 100 in operating, connects a source of ringing current 91 through the local trunk circuit C, causing the operation of relay 92, whereupon relay 93 is energized connecting a source of ringing current 94 at the local 105 office F to the called line. Ringing current remains connected to the called line only as long as the operator at central office X keeps ringing key 80 operated.

In response to the operation of the call 110 bell at the subscriber's station, the subscriber removes the receiver from the switchhook, causing the operation of supervisory relay 95, which removes the short circuit of resistance 96, whereupon relay 75 115 receives a reduced flow of current and releases. The release of relay 75 removes the short circuit from the righthand winding of relay 25 and resistance 73, thereby reducing the amount of current through relay 23 120 causing the release thereof. Relay 25 remains operated. Relay 23, in releasing, causes the release of relay 38, thereby extinguishing the supervisory lamp 37.

At the termination of the conversation 125 when the receiver at the called station is restored to the switchhook, relay 38 is again energized, relighting supervisory lamp 37, which serves as a disconnect signal to the operator at central office X. The operator 130

now withdraws the plug 6 from the jack 7, whereupon relays 15, 17 and 18 release. The release of relay 18 opens the circuit from negative signaling battery, whereupon relay 22 and 25 release. As before explained, relay 26 is slow in releasing, so that upon the release of relay 25 the release magnet 30 of the selector operates to withdraw the holding pawl 65 from the ratchet wheel, thereby permitting the wiper 64 to return to normal position. Relays 56 and 57 are thereby released. The release of relay 56 causes the release of relay 76, whereupon supervisory lamp 77 lights to furnish a disconnect signal to the operator at the local office F, who then withdraws the plug of the local trunk from the jack of the line, restoring all of the apparatus to normal.

The call wire circuits D from the central office Y to the local offices E, F, G and H are used in handling connections originating in the central office Y and may be multiplied through the different operators' positions. 100 represents a call wire key at one such operator's position. Actuation of key 100, if the call wire circuit is not busy, causes the actuation of relay 101 over a circuit from battery through the contact and left-hand winding of relay 71, lower contact of key 100, winding of relays 101 and 102 to ground. Relay 102 does not operate because relay 101 in operating closes its lower alternate contact 103, short-circuiting relay 102 and causing the operation of relay 71. The operation of relay 101 also connects the operator's telephone set at the central office Y to the call wire circuit D extending to the local office F. Relay 71, in operating, removes the normal short circuit of the right-hand winding thereof, thereby including both windings in circuit. Should this call wire circuit have been busy when the operator at the central office Y actuated key 100, both windings of relay 71 would have been in circuit, thereby preventing the operation of relay 101. Relay 102 would, however, have operated, lighting the lamp 104 and operating relay 105. The lighting of the lamp 104 indicates to the operator that the call wire circuit is in use, and the operation of relay 105 connects a tone to the receiver of the operator's telephone set, which also indicates to the operator that the call wire circuit is in use.

Should the call wire circuit D extending to the local office F have been busy when the operator at central office X actuated listening key 39 and selecting key 41 to select local office F, the prior operation of relay 71 would have prevented the operation of relay 70, but relay 72 would have operated. Relay 72 operating, would have connected a tone to the normal contacts 106 and 116 of relay 70, whereby a tone would have been transmitted to the receiver of the operator's telephone set at the central office X, indicating to this operator that the call wire circuit D extending to the local office F was in use.

Suppose that, while a connection is set up through the central offices X and Y and the local office F to a subscriber's station of this local office, the operator at central office X should receive another call for connection to a subscriber's line terminating in one of the local offices E, F, G or H, which second connection would necessitate the use of the main trunk circuit B, the operator would insert a calling plug of a second call circuit A into jack 107 of a main trunk circuit B. No apparatus associated with the main trunk circuit B is operated by the insertion of a calling plug of a second cord circuit into the jack 107 while another calling plug is connected to the jack 7, for the energizing circuit of relay 16 is open at a contact of relay 15. As soon as the operator at the central office X receives the disconnect signal by the lighting of supervisory lamp 37 in the cord circuit A connected to jack 7, the calling plug 6 is withdrawn from the jack 7. Relay 90 15 releases, causing the release of relays 17 and 18 and the operation of relay 16. The operation of relay 16 causes the operation of relay 117 to connect the tip and ring conductors of the main trunk circuit B to the tip and ring contacts of the jack 107. Relay 16 in operating, also causes the operation of relay 18. Relay 18 had, however, released before its circuit was again completed by the actuation of relay 16. The momentary release of relay 18 due to the release of relay 15, before its operation due to the operation of relay 16, causes the momentary release of relay 25, which in turn causes the operation of the release magnet 30 to withdraw the holding pawl 65 from the ratchet wheel so that the wiper 64 returns to normal position. Upon the return of the wiper 64 to normal, relays 56, 57, 75 and 76 are released. The release of relay 75 causes the lighting of lamp 77 to furnish a disconnect signal to the operator at the local office F, who then withdraws the plug from the jack. The operation of relay 18, due to the operation of relay 16, causes the operation of relays 22 and 25, as hereinbefore explained. The operator at central office X may then actuate listening key 39 and one of the keys of the impulse transmitter 36 to select the desired local office.

After having communicated to the operator at the selected local office the number of the desired subscriber's line, and after having released the selecting key, the operator at the first central office may find that the wrong number has been transmitted to the operator at the local office, that the wrong local office has been selected, that

the right local office has been selected but that the operator thereat has connected the local trunk circuit to the wrong subscriber's line, or the right subscriber's line may have 5 been connected with but the subscriber did not respond. In such cases, it is desirable that the first central office operator may be able to communicate with the operator at the desired local office without having to 10 withdraw the plug of the cord circuit from the jack of the main trunk circuit B. This is especially desirable for the reason that a second cord circuit may be connected with the second jack of the main trunk circuit.

15 The present invention provides for the contingencies above mentioned. Assuming, for example, that the proper local office has been selected and that the operator thereat has connected the incoming end of the local 20 trunk circuit C to the wrong subscriber's line, and assuming further that the office selected is local office F, the operator at the central office X may actuate listening key 39, and selecting key 41, which causes the actuation 25 of relay 27 over a circuit from battery through the winding of relay 44, lower contact of key 41, upper contact of listening key 39, tip conductors of the cord circuit A and the main trunk circuit B, and both 30 windings of relay 27 to ground. The operation of relay 27 releases relay 18, which releases relays 22 and 25, the release of relay 22 short-circuiting the high resistance winding of relay 27, causing the operation of 35 starting relay 44 of the impulse transmitter 36. The release of relay 25 releases relay 26, but, as before explained, since relay 26 is slow in releasing, a circuit is completed for the release magnet 30 of the selector 60, 40 whereupon the holding pawl 65 is withdrawn from the ratchet wheel 63 permitting wiper 64 to return to normal position, whereupon relays 55, 56 and 57 release. Thereafter the local trunk circuit from the central 45 office Y to the local office F is selected in the manner hereinbefore described, and the main trunk circuit B is connected to the call wire circuit D extending to the operator's telephone set at local office F. The operator at central office X may then rein- 50 struct the operator at local office F as to the connection desired.

What is claimed is:

1. In a telephone system, a main trunk circuit extending from a first to a second central office, local trunk circuits and associated call wire circuits, one of each extending from the second central office to each of a plurality of local offices, a step-by-step selector at the second central office controlled from the first central office to select one of said local trunk circuits, and apparatus operating upon the selection of a local trunk circuit to connect said main trunk circuit

with the call wire circuit associated with the selected local trunk circuit. 65

2. In a telephone system, a main trunk circuit extending from a first to a second central office, local trunk circuits and associated call wire circuits, one of each extending from the second central office to each of a plurality of local offices, a step-by-step selector at the second central office controlled from the first central office over said main trunk circuit to select one of said local trunk circuits, and relays operating upon the selection of a local trunk circuit to connect the main trunk circuit with the call wire circuit associated with the selected local trunk circuit. 70

3. In a telephone system, a main trunk circuit extending from a first to a second central office, local trunk circuits and associated call wire circuits, one of each extending from the second central office to each of a plurality of local offices, an impulse transmitter at the first central office, a step-by-step selector at the second central office responsive to impulses from said impulse transmitter transmitted over said main trunk circuit to select one of said local trunk circuits, and apparatus operating upon the selection of a local trunk circuit to connect said main trunk circuit with the call wire circuit associated with the selected local trunk circuit. 85

4. In a telephone system, a main trunk circuit extending from a first to a second central office, local trunk circuits and associated call wire circuits, one of each extending from the second central office to each of a plurality of local offices, an impulse transmitter at the first central office, a source of signaling current thereat, a relay associated with the main trunk circuit at the first central office responsive to current impulses from the impulse transmitter to intermittently connect said source of signaling current with the main trunk circuit, a step-by-step selector at the second central office responsive to signaling current impulses over the main trunk circuit to select one of said local trunk circuits, and apparatus operating upon the selection of a local trunk circuit to connect said main trunk circuit with the call wire circuit associated with the selected local trunk circuit. 100

5. In a telephone system, a main trunk circuit extending from a first to a second central office, local trunk circuits and associated call wire circuits, one of each extending from a second central office to each of a plurality of local offices, a link circuit, an impulse transmitter and a source of signaling current at the first central office, a relay associated with the main trunk circuit at the first central office responsive to current impulses from said impulse transmitter when said link circuit is connected with said 110

main trunk circuit, said relay intermittently connecting said source of signaling current to the main trunk circuit, a step-by-step selector at the second central office responsive to signaling current impulses over the main trunk circuit to select one of said local trunk circuits, and relays operating upon the selection of a local trunk circuit to con-

nect said main trunk circuit with the call wire circuit associated with the selected local trunk circuit.

In witness whereof, I hereunto subscribe my name this 6th day of October, A. D., 1915.

EDWARD E. HINRICHSEN.
